UNITED STATES PATENT OFFICE.

LESLIE P. FARMER, OF SOUTH ORANGE, NEW JERSEY.

RAILROAD-CAR.

SPECIFICATION forming part of Letters Patent No. 432,265, dated July 15, 1890.

Application filed February 28, 1890. Serial No. 342,125. (No model.)

To all whom it may concern:

Be it known that I, LESLIE P. FARMER, of South Orange, Essex county, State of New Jersey, have invented a new and useful Im-

5 provement in Railroad-Cars, of which the following is a true and exact description, reference being had to the accompanying drawings, which form a part of this specification.

My invention relates to the construction of 10 railroad passenger-cars, and has for its object to improve the same and obviate some of the disadvantages incident to the mode of construction now generally adopted.

15 The leading novel feature of my improved car lies in the construction by which I am enabled to form the doorways for entering and leaving the car in the sides thereof and to combine with them steps leading up from the doorway to the floor of the car, situated 20 entirely within the car. This and the other novel feature of my improved car will be best understood as described in connection with the drawings in which they are illustrated, and those features which I desire to protect 25 by Letters Patent are hereinafter clearly set forth in the claims.

In the drawings, Figure 1 is a side elevation of my improved car, partly broken away, so as to show both the center and the ends of 30 the car in the same view. Fig. 2 is a plan view of the car on the line xx of Fig. 1. Fig. 3 is a sectional elevation taken on the line yy of Fig. 1. The half of the car is shown in this view, the other half being, of course, 35 exactly similar. Fig. 4 is a perspective view of a portion of the inside of the car, showing certain of the appliances which I prefer to use in connection with the side entrances. Figs. 5 and 6 are, respectively, a plan and 40 edge view of a yoke-rail used in connection with my device. Fig. 7 is a perspective view of one of the **U**-shaped braces used by me to connect the ends of the intermittent longitudinal sills. Fig. 8 is a perspective view showing 45 the intermittent longitudinal sills and the **U**-shaped braces attached to them. Fig. 9 is an elevation showing the end sill of the car and the wheels for actuating the brake and the uncoupling device. Fig. 10 is a side elevation showing how the uncoupling-wheel 50 can be secured inside of the car and the con-

nections made therefrom, and Fig. 11 is a plan view showing the relative arrangement of the brake-wheel and uncoupling-wheel and their connections with respect to the car. 55

As is the car, the platform-base of which has the usual longitudinal sills B B' B^2 , &c., extending throughout its length. I have designated the extreme edge sill by the letter B and the one immediately adjacent to it by 60 the letter B' , the central sills being designated by the letter B^2 . Instead of continuing the sills B and B^2 on the same level throughout the length of the platform, I intermit them or make them in two parts, as 65 shown, connecting their ends by means of **U**-shaped braces C or C' . These braces are placed at the point in the length of the car at which it is desired to form a side entrance or doorway, such a doorway being 70 designated by the letter D . The breadth of the **U**-shaped braces C , which connect the intermitted parts of the edge sill B , is preferably made substantially equal to twice the breadth of the desired doorway, and the ends 75 of the connected parts of sill B are cut away, as is shown at b b , so as to permit sliding doors E to be pushed back beyond the sides of the doorway which they close. The brace C' need have no greater breadth than that of the 80 desired doorway or passage leading from it.

To the bottoms of the braces C and C' , I secure angle-irons F to afford a better support for the door-posts and other appliances which are secured to the hangers. The doors 85 E preferably run upon wheels or rollers e , (see Fig. 1,) secured to or above the angle-irons F . Leading up from the bottom of the brace C and over the brace C' are steps G , running to the surface or floor of the car-platform, the floor being designated by the letter H . Preferably the doorways and steps in the sides of the car are made to face each other, as shown in the drawings, and when so constructed I prefer to secure tracks J J along 95 the sides of the steps and across the bottom of the car slightly below the level of the floor, and to provide a sliding platform K , running upon said tracks by means of wheels k , and which can be pushed from one side of 100 the car to the other. The length of this platform should not be greater than the distance

between the top of one set of steps and the side of the car upon the opposite side. I believe it will be found most convenient to make the platforms of this length, though 5 they will serve the purpose for which I intend them if they are only broad enough to cover one of the sets of steps. The use of this platform is to cover over and close one set of steps whenever the other opposite set 10 is uncovered, thus at the same time preventing passengers from going down the wrong steps, and also forming a floor over the steps not in use, so that the passengers will not fall or be pushed down them, and also to permit 15 passengers to occupy said platform, enabling them to pass quickly down the steps when the train has reached a station. It is readily pushed from one side or the other, so as to open the steps on either side of the car that 20 may be desired.

I are panels extending up into the car-body alongside of the steps, preferably to the height of the back of the seats in the car. Across the ends of these panels it is desirable 25 to secure a removable rail, which can be adjusted in place when the car is in motion, in order to close the entrance to the steps. As shown in the drawings, a yoke L is pivoted at l' l' to slotted links l², which are secured to the sides of the car or to the sides 30 of the panels I by pins l³. When it is desired to close the steps, the yoke is turned upon its pivots to the position indicated in Fig. 4 and in dotted lines in Figs. 3 and 2. The 35 portions l then extend across the top of the steps, forming a hand-rail and effectually preventing any one from slipping down them. The yoke is readily thrown up and is retained by a catch l⁴, (see Fig. 3,) the slotted 40 links l² permitting it to rise, so that it really hangs upon the said hook or catch l⁴.

I' I' are hand-rails secured to the panels I, and d d rails secured on the outside of the doorway for the convenience of passengers in 45 entering.

In cars having side entrances such as above described the ordinary end platforms upon the outside of the cars can be entirely dispensed with, a projecting end sill or narrow 50 platform, such as Q, being amply sufficient for all the uses to which such a platform will, in the new construction of cars, be put to.

The brake-wheel and coupling-unlatching devices may, if desired, be secured upon the 55 outside of the car; but I prefer to place them on the inside and at the ends of the car, as shown in the drawings, in which S indicates the brake-wheel, and T a wheel which actuates mechanism for unlatching the coupling 60 devices by which the cars are united. The closets O and O', used to inclose the heater and for other purposes, are situated, as usual, in the ends of the car, and doors N are also provided in the ends to enable the train-men or 65 passengers to pass from car to car. As these doors, however, will be but little used, I divide the ends of the car containing the closets and

the wheels S and T from the main body thereof by doors P P and by the walls of the closets.

The connections made from the wheels S and T are illustrated in Figs. 9, 10, and 11. The brake-connection is made direct from the shaft of wheel S by means of a chain s. The connection from wheel T is made by means 75 of a chain t, secured to its shaft and passing down through the floor of the car to connect with a bell-crank lever t'. From this lever a chain t², passing over a pulley t³, connects with the latch t⁴, such as is used for latching 80 and unlatching couplers of the vertical plane type. Another chain t⁵ also connects with bell-crank lever t', and has a hook at its end by which it can be connected with a lug t⁶ on a Miller coupler. When this chain is not in 85 use, it can be connected to an eyebolt t⁷, as shown in Fig. 9.

R R, &c., are elastic gates, one of which is hinged at r' to each end of the car and upon opposite sides thereof, all the cars being similarly equipped, so that when two abut together, as is indicated at the right of Figs. 1 and 2, a gate R will extend between two cars on each side of the narrow platform. Catches r are provided on the opposite sides of the car 95 to those at which the gates are hinged to engage the free end of the gate. The passage between the cars is thus railed on both sides.

U U are hoods or curtains supported on pivoted levers, as shown, and which overlap each 100 other when two cars are coupled, so as to form a covered way between the two cars.

V, Fig. 1, indicates one of the lamps which light the inside of the car. It is desirable that one should be placed between the steps, 105 as indicated in Fig. 1, so as to throw its light directly down the same.

Among the advantages incident to my new form of railroad-car may be noted the fact that the steps for entering and leaving the 110 car can extend lower down and at the same time rise more easily and gradually than the steps used with the end platforms. The steps and doorway may also be made considerably wider than the steps and platform at the end of 115 the car. For both of these reasons, and also by reason of the situation of the steps within the car, the passengers can enter and leave the same much more rapidly than in the present usual construction. It is very advantageous 120 also to have the steps completely inclosed in the car, as they are thus kept dry and clean, and the passengers step directly from the inside of the car to the station-platform. My construction also avoids the objectionable drafts incident to opening the end doors on approaching stations. The steps are also better lighted and without requiring any additional lighting devices besides those used to light the car. The car is also made larger without any increase in the length of its platform. The necessity or desirability of a vestibule between two cars is obviated, as by my construction 130 the car-bodies come so close together that the

short passage is easily protected without requiring the vestibuling of the platforms. As the brakeman will stand in the center of the car when announcing stations, he will be much 5 more easily heard than when announcing them from the end of the car, as is now the case.

Another important advantage incident to the construction shown is that passengers are 10 compelled to leave and enter the car on the station or platform side, and also that it is made impossible for passengers to get upon the car when the doors are closed.

Having now described my invention, what I 15 claim as new, and desire to secure by Letters Patent, is—

1. A railway-car having its central longitudinal sills continuous and its outer longitudinal sills made in two parts connected by 20 downwardly-extending U-shaped braces, doorways formed in the sides of the car over said braces, and steps situated over said braces and leading up inside the car to its continuous central passage, substantially as 25 specified.

2. A railway-car having its central longitudinal sills continuous, its extreme outer longitudinal sills made in two parts with an opening between them substantially equal to twice 30 the breadth of the doorway, and one or more adjacent sills also severed, as described, U-shaped downwardly-extending braces connecting the severed sills, a doorway leading into the car over the outer braces, sliding

doors arranged to close said doorway and to 35 slide back over the outer brace, and steps leading from said doorway over the braces to the continuous central passage of the car, all substantially as specified.

3. In combination with a railway-car having 40 opposite side entrances and steps leading up inside the car, as described, tracks extending across from entrance to entrance slightly below the level of the car-floor, and a sliding platform supported on said tracks and of 45 sufficient length to cover one set of steps when pushed over to uncover the opposite sets.

4. In combination with a railway-car having 50 opposite side entrances and steps leading up inside the car, as described, side panels extending up into the body of the car alongside the steps, and a removable rail or its equivalent adjustable across the panels at the top of said steps, substantially as and for the purpose specified.

5. In combination with a railway-car having 55 opposite side entrances and steps leading up inside the car, as described, side panels extending up into the body of the car alongside the steps, and a yoke-rail pivoted near the door and adapted to extend across the panels at the top of the steps when lowered, substantially as and for the purpose specified.
